Harry H. Denean

UNITED STATES PATENT OFFICE.

NOEL STATHAM, OF IRVINGTON, NEW YORK.

RAZOR AND STROPPING DEVICE.

Application filed August 30, 1919. Serial No. 320,834.

To all whom it may concern:

Be it known that I, NOEL STATHAM, a subject of the King of Great Britain, now residing at Irvington, county of Westchester, 5 State of New York, have made a certain new and useful Invention Relating to Razors and Stropping Devices, of which the following is a specification, taken in connection with the accompanying drawing, 10 which forms part of the same.

This invention relates especially to safety razors and combined stropping devices in which the razor handle, which may be advantageously formed of sheet metal, may 15 have a corresponding sheet metal blade holder movably mounted thereon and preferably permanently connected thereto, as by hinging the blade holder to a hinge support which may be pivoted to the handle. 20 In this way the blade holder and razor blade which may be held therein, may, for stropping purposes, be swung substantially into the plane of the adjacent portion of the handle and retained in this stropping 25 position as by a corresponding retaining device or recess in the handle, enclosing an adjacent end of the blade holder. After the razor blade has been sharpened the holder may be released from this stropping 30 position and swung out of the plane of the handle and held in any such desirable shaving position in connection with a guard detachably cooperating with the blade and holder and preferably having a locking device 35 which may be conveniently snapped around the end or other part of the handle to hold the parts in this shaving position.

In the accompanying drawing showing in a somewhat diagrammatic way various 40 illustrative embodiments of this invention.

Fig. 1 is a perspective view showing the razor in shaving position,

Fig. 2 is a corresponding enlarged longitudinal section thereof,

Fig. 3 is a front view showing the handle and connected holder and blade in such relative position that the parts may be swung into the stropping position as shown in Fig. 5,

Fig. 4 is a bottom view of the detachable guard,

Fig. 5 shows the Fig. 3 construction with the blade and blade holder swung into stropping position,

Figs. 6 and 7 are perspective views illustrating the stropping of the razor,

Fig. 8 shows the razor in folded position in which it may be packed or carried; and

Fig. 9 shows another carrying position 60 of the razor together with an enclosing strap.

By making the handle of the razor of thin sheet metal lightness and compactness are promoted and this handle 1 may preferably be formed with a double thickness pivot portion in which the two layers or thicknesses of sheet metal 16, 17 may be somewhat separated if desired. The blade holder 12, which may also advantageously be 70 formed of thin sheet brass or other resilient material, is preferably loosely mounted on the handle while permanently connected thereto, so that the blade holder is foldably and swingingly connected to the handle. 75 This may be effected by providing a hinge support such as the plate or sheet 14, pivoted as by the pin 15, to the handle and preferably located between the double thicknesses of the pivot portion of the handle as 80 illustrated in Figs. 2 and 3. A hinge joint 13 may be provided between this hinge support 14 and the blade holder, or a hinge member 21 which may be soldered or otherwise connected to the blade holder. Thus 85 the blade holder is permanently connected to the handle and may fold out into angular position with respect thereto by moving about its hinge connection with the hinge support, and also the blade holder together 90 with its connected hinge support may swing about the pivot 15 so that the edge of the razor blade in this holder may assume any desired angular position with respect to the length of the handle. This is illustrated in 95 Figs. 3 and 5, since when the blade holder and cooperating blade 19 have been folded or opened out about the hinge joint into substantially the plane of the handle, these parts may then be swung about the pivot 100 15 in the direction indicated by the arrows in Fig. 3, until the blade edge becomes sub-

stantially parallel to the length of the handle as indicated in Fig. 5, the recess 22 in the handle member 16, being provided to accommodate the hinge 18 under these conditions. The blade holder and blade may be held in this stropping position by any suitable retaining device, and for this purpose a resilient gripping retaining device or recess may be conveniently provided by the 10 wedging opening 18 formed between the two thicknesses of the handle material at this point, so that the blade holder may enter this opening which is shown in Fig. 1, and be wedged tightly enough between these 15 resilient sheet metal portions to be properly retained in this stropping position, the resilient pressure against the sides of the blade holder also serving to hold the razor blade more tightly in position thereon. This arrangement makes it easy to strop or sharpen the razor blade without removing it from the blade holder and as indicated in Fig. 6 this may be accomplished by drawing the blade holder and blade along a strop such 20 as 23 so that the edge 19 of the razor blade engages the strop sufficiently for sharpening contact therewith during this stroke, then, if desired, the razor may be brought back and drawn down again beneath the strop 25 as indicated in Fig. 7 so that both sides of the razor edge may be stropped or sharpened alternately,

For shaving purposes, the razor blade and holder may be disengageably supported in any desired angular position with respect to the handle, preferably in connection with a suitable guard member properly cooperating with the blade edge. As indicated in Figs. 1, 2 and 4 the guard member 2 of sheet brass or other suitable material, may be provided with projecting lateral portions or flanges 6 in which guide channels 8 may be formed to engage or cooperate with the edges of the blade holder 12, and, if desired, the ends of these flanges may constitute aligning shoulders with which the aligning lugs or portions 20 of the razor blade may engage as indicated in Fig. 1 to accurately position or align the blade with respect to the guard member. These lugs may also be used to align the blade within the blade holder which may be formed with recessed portions 24 with which these lugs may engage as indicated in Fig. 3. The guard member may be formed with a locating edge or member 5 adapted to engage the blade holder adjacent the edge of the blade and a cooperating guard lip or portion 4 may be arranged in advance of the razor edge 30 so as to provide a suitable interval or space 3, as indicated in Fig. 2. This guard lip may, of course, be given any suitable form, and as indicated in Fig. 1, depressed or recessed portions 25 of any suitable shape may 35 be formed therein so as to form more or less

separated contact portions, giving the desired contact with the lathered surface of the skin. It is sometimes desirable to form the detachable guard member with a retaining spring such as 7 to engage the blade holder or blade and prevent accidental separation of these parts and it is also desirable to form one or more locking devices such as 10 on the guard member so as to have locking or gripping cooperation with any 15 desired part of the handle and hold the blade holder and blade in shaving position with respect thereto. As indicated in Fig. 1 when the blade holder and guard are swung up away from the plane of the handle the resilient locking device 10 snaps over the yielding end 17 of the handle from which it may be readily disengaged by pressure on the projection 11 of this locking device. When thus released the blade holder and 20 guard may be swung down against the handle which gives a flat compact position of the parts for traveling; for instance, and by swinging the blade holder around the pivot 25 substantially into line with the handle, 30 a still greater compactness is secured, since the device then has practically the same width as the handle itself, as indicated in Fig. 9. The razor strop such as 23 may, of course be wrapped around the razor when 35 in this folded position so as to protect the razor and guard its cutting edge and the strop may be held by an elastic loop 26 on the strop so that a very compact razor and strop may thus be secured for a travelling 40 or portable outfit.

This invention has been described in connection with a number of illustrative embodiments, parts, proportions, materials, devices, arrangements and methods of manufacture and use, to the details of which disclosure the invention is not of course to be limited, since what is claimed as new and what is desired to be secured by Letters Patent is set forth in the appended claims.

I claim:

1. In safety razors and stroppers, a handle having a double thickness pivot portion, a resilient gripping sheet metal blade holder, a hinge support hinged to said blade holder and pivotally mounted between the double thickness of the pivot portion of said handle, a razor blade detachably held and aligned in said blade holder, a retaining device on said handle to hold one end of said blade holder when said holder and blade are swung substantially into the plane of the handle for sharpening purposes, and a guard member adapted to be detachably connected with said blade and holder and a resilient locking device on said guard member to detachably engage said handle and hold said guard member and blade in shaving position.

2. In safety razors and stroppers, a han-

dle having a double thickness pivot portion, a gripping sheet metal blade holder, a hinge support hinged to said blade holder and pivotally mounted between the double thickness of the pivot portion of said handle, a razor blade detachably held in said blade holder, a retaining device on said handle to hold said blade holder when said holder and blade are swung substantially into the plane of the handle for sharpening purposes, and a guard member adapted to be detachably connected with said blade and holder and a resilient locking device to hold said guard member and blade in shaving position.

3. In safety razors and stroppers, a handle, a gripping blade holder, a hinge support hinged to said blade holder and pivotally mounted on said handle, a razor blade detachably held in said blade holder, a retaining device on said handle to hold said blade holder when said holder and blade are swung substantially into the plane of the handle for sharpening purposes, and a guard member adapted to be detachably connected with said blade and holder.

4. In safety razors and stroppers, a handle, a gripping blade holder foldably and pivotally mounted on said handle, a razor blade detachably held and aligned in said blade holder, a retaining device to hold said holder and blade substantially in the plane of the adjacent portion of the handle for sharpening purposes, a guard member adapted to be detachably connected with said blade and holder, said guard member having guide channels to receive the lateral edges of said blade holder and having a locating edge to engage said blade holder adjacent the blade edge and a cooperating guard lip formed with separated contact portions in front of the edge of said blade, and a resilient locking device on said guard member to detachably engage said handle and hold said guard member and blade in shaving position.

5. In safety razors, a handle, a gripping blade holder foldably and pivotally mounted on said handle, a razor blade detachably held and aligned in said blade holder, a guard member adapted to be detachably connected with said blade and holder, said guard member having guide channels and a locating edge adjacent the blade edge and a cooperating guard lip formed with separated contact portions in front of the edge of said blade, and a locking device on said guard member to detachably engage said handle and hold said guard member and blade in shaving position.

6. In safety razors and stroppers, a handle, a blade holder adapted to receive a razor blade, a hinge support hinged to said blade holder and pivotally mounted on said handle, a retaining device to hold said blade

holder substantially in the plane of the handle for sharpening purposes, a guard member adapted to be detachably connected with said blade holder, and a locking device adjacent the hinge joint between said members to hold said guard member and blade in shaving position with respect to said handle.

7. In safety razors and stroppers, a handle, a blade holder foldably and swingingly connected to said handle, a razor blade detachably mounted in said blade holder, a retaining device to hold said blade substantially in the plane of the adjacent portion of the handle for sharpening purposes and means adjacent the foldable joint between said blade holder and said handle to releasably hold said blade in shaving position with respect to said handle and at a substantial angle thereto.

8. In safety razors and stroppers, a handle having a substantially flat connecting portion, a blade holder having a hinge joint foldably mounting it on said handle connecting portion, a razor blade detachably mounted in said blade holder, a resilient retaining device to hold said blade substantially in the plane of the adjacent connecting portion of the handle for sharpening purposes and holding means adjacent said hinge joint to releasably hold said blade in shaving position with respect to said handle and projecting at a substantial angle therefrom.

9. In safety razors, a handle having a substantially flat connecting portion, a blade holder having a hinge joint foldably mounting it on said handle connecting portion, a razor blade detachably mounted in said blade holder, and holding means adjacent said hinge joint to releasably hold said blade in shaving position with respect to said handle and projecting at a substantial angle therefrom.

10. In safety razors and stroppers, a handle having a substantially flat connecting portion, a substantially flat blade holder having a hinge joint foldably mounting it on said handle connecting portion and adapted to releasably support a razor blade, a device to hold said blade holder substantially in the plane of the adjacent connecting portion of the handle and locking means adjacent said hinge joint to releasably hold said blade holder in shaving position with respect to said handle and projecting at a substantial angle therefrom.

11. In safety razors, a handle having a substantially flat connecting portion, a substantially flat blade holder having a joint foldably mounting it on said handle connecting portion and adapted to releasably support a razor blade, a device to hold said blade holder substantially in the plane of the adjacent connecting portion of the han-

dle and locking means adjacent said joint to releasably hold said blade holder in shaving position with respect to said handle and projecting at a substantial angle therefrom.

12. In safety razors, a handle having a substantially flat connecting portion, a substantially flat blade holder having a joint foldably mounting it on said handle con-

nnecting portion and adapted to releasably support a razor blade and means adjacent 10 said joint to releasably hold said blade holder in shaving position with respect to said handle and projecting at a substantial angle therefrom.

NOEL STATHAM.
